ROTATABLE DISK PICTURE TOY AND GAME

Alexander Rosenfeld, Hollywood, Calif.

Application October 15, 1958, Serial No. 52,980

Term of patent 3½ years

(Cl. D34—15)

Figure 1 is a front elevational view of a rotatable disk picture toy and game showing my new design.

Figure 2 is a vertical sectional view taken on line 2—2 of Figure 1.

Figure 3 is a rear elevational view of Figure 1.

I claim:

The ornamental design for a rotatable disk picture toy and game, as shown.
